UNITED STATES PATENT OFFICE.

WILLIAM NEES, OF DREXEL HILL, PENNSYLVANIA.

DIES FOR FORMING THROAT SHEETS FOR BOILERS.

Application filed June 8, 1927. Serial No. 197,496.

My invention relates to certain improvements in dies used in forming throat sheets of locomotive boilers. Throat sheets of locomotive boilers are so shaped that they require 5 dies having different shaped nose pieces to properly turn the flanges and are difficult to remove from the dies after being formed unless the upper die is raised to an extreme height, making it necessary to provide a very 10 long stroke press.

One object of my invention is to provide the upper die with a removable section, which can be detached and another substituted therefor, and to so arrange the upper die that 15 the nose section can be moved in such a manner that a formed throat sheet can be withdrawn laterally from the lower die.

A further object of the invention is to so construct the upper die that the nose section 20 can be turned on a pivot.

In the accompanying drawings:

Fig. 1 is a side view of an upper and a lower die, showing the upper die in position to press a sheet metal blank into the form 25 of a throat sheet;

Fig. 2 is a front elevation of the two dies;

Fig. 3 is a side view of the first movable nose section of the upper die;

Fig. 4 is a side view of the second movable 30 nose section;

Fig. 5 is an end view of the third movable nose section;

Fig. 6 is a front view of one-half of the nose section shown in Fig. 5; and

Fig. 7 is a perspective view of a throat 35 sheet formed by the dies.

1 is the lower die made in two parts 2—2. The lower die has an inclined semi-circular depression 3 conforming to the shape of the 40 body portion *a* of the throat sheet, Fig. 5, and the front face is inclined as at 4, Fig. 1, being at an angle to the depression 3. The upper edge of the lower die is rounded at the forward end as at 5, so that when the sheet metal blank is pressed into the lower die, it 45 will produce a flange *b* and a curved connection *c* between the body *a* and the flange.

6 is the upper die, having a curved portion 7 conforming to the semi-circular recess 3 50 of the lower die, so that the semi-cylindrical metal blank is held when the upper and lower die terminates in a rounded section 8 which

conforms to the section 5 of the lower die. The nose piece 9 of the upper die is made separate from the main body of the die, so as to 55 be interchangeable with other nose pieces as conditions may require.

As shown in Fig. 1, the nose piece is hinged so that it can swing clear of the formed throat sheet after the blank has been pressed 60 into shape, in order that the finished throat sheet can be readily removed laterally from the lower die when the upper die is elevated a sufficient distance to clear the finished sheet. In Figs. 1 and 2 I have shown the nose piece 65 9 made in two parts 10—10 and hinged at 11 to the upper die, so that the nose piece can be raised in position as shown in dotted lines in Fig. 1, to allow for the ready removal of the throat sheet without raising the die to an extreme position. The nose piece is held firmly in its lower inactive position by pins 12, which pass through openings in a flange on the body portion of the upper die 6 and openings in a flange on the nose piece 9. Other 70 75 means of fastening the parts together may be used without departing from the scope of the invention.

In some instances the nose piece may be bodily removed from the upper die when it is 80 necessary to remove the finished throat sheet from the lower die.

In the present instance the throat sheet shown in Fig. 7 requires several operations, using nose pieces of different lengths. The 85 flange is first partly formed by a die having a fixed nose piece. Then a short nose piece, Fig. 3, is attached to the upper die so as to further bend the flange of the heated blank. Then a longer nose piece, shown in Fig. 4, is 90 attached to the upper die and the operation repeated. Then a still longer nose piece, shown in Figs. 5 and 6, is attached to the upper die and the flange is forced down in position against the lower die. The number of 95 operations will depend upon the depth of the flange and the thickness of the metal of the throat sheet.

The blank is first bent into semi-cylindrical shape before being placed in the dies, and is 100 preferably heated between each pressing operation. The dies in the present instance form the main flange *b* and the side flanges *d*—*d*, but it will be understood that the dies

can be shaped to form different types of flanges without departing from the main features of the invention.

I claim:

- 5 1. The combination in a die for forming sheet metal having a body portion and a deep flange, such as a throat sheet of a locomotive boiler, of a lower die having a segmental cavity and a face to form the flange of the blank; and a single upper die conforming to the shape of the lower die and having a movable nose section arranged to be moved from the path of the formed blank so that the flanged piece can be removed from the lower die.
- 10 15 2. The combination in means for forming throat sheets of locomotive boilers, of a lower die having an inclined segmental cavity to receive the body of the throat sheet; an inclined surface on which a flange is formed; a single

upper die conforming to the shape of the lower die; a nose piece pivotally connected to the upper die; and means for retaining the nose piece in its active position.

3. The combination of a lower die having a segmental cavity conforming to the shape of the body portion of the throat sheet of a locomotive boiler, said cavity being on an incline, the end face of the die being at an angle to the inclined surface of the body of the die, the upper die conforming to the shape of the lower die and having a hinged nose piece extending over the end face of the die, the die and nose piece being flanged; and detachable pins extending through the two flanges and securing the two parts firmly together in the active position.

WILLIAM NEES.
